UNITED STATES PATENT OFFICE.

GEORGE CLAUSING, OF PORTSMOUTH, OHIO, ASSIGNOR, BY MESNE ASSIGNMENTS, TO
VULCAN CORPORATION, OF PORTSMOUTH, OHIO, A CORPORATION OF OHIO.

HEEL-TURNING MACHINE.

Application filed November 14, 1927. Serial No. 233,163.

My invention relates to a heel turning machine.

It is the object of my invention to provide a heel turning machine with mechanism for obtaining the inclined and vertical positions of the jack on a heel blank holder, which can be positioned and maintained in position as desired, eliminating the tracks and other complicated mechanism previously employed.

Such tracks are difficult to adjust accurately, are expensive to build, and, due to their wear, make it difficult to maintain an accurate adjustment.

It is my object to provide a simple, cheap and easily adjusted mechanism that may be controlled and operated by a mechanic of ordinary experience.

With the adjustable features of these means for adjusting the inclined and vertical positions of the heel blank holder, all positions desired can be secured without the use of a variety of tracks so that one set of link mechanism will take the place of any number of tracks.

Referring to the drawings:

Figure 1 is a side elevation with a part of the frame in section;

Figure 2 is a top plan view of the machine with the heel holder directly in front of the operator;

Figure 3 is a similar view with the heel holder to one side of the machine with a heel blank in position to be dressed on the side thereof by one of the cutting knives.

Referring to the drawings in detail, 1 constitutes a frame on which is mounted a support 2, such support acting as a carrying mechanism for some of the elements of this heel turning machine. The top of the support rests upon the table 3.

A belt 4 driven by any suitable source of power engages with a pulley 5 on the vertical shaft 6 which carries one of the cutting knives 7. Bearing sleeves 8, 9 and 10 are mounted on the vertical support 2. Adjacent each of the cutting knives is an adjustable guard 11 held in position by a bolt 12 and adapted to be moved when unbolted by the set screw 13. The guard end 14 of the adjustable guard is adapted to engage with the heel holder.

The support 2 carries a pair of vertically aligned, horizontally disposed sleeves 15 in which are mounted respectively the slides 16

and 17 between the knife shafts 6. The slides 16 and 17 may be adjusted in the sleeves 15 and held therein by any suitable means. By using the slides 16 and 17 in the sleeves 15 the shaft 22 may be adjusted in relation to the vertical.

The slide 16 is provided with a jaw 18 at its outer end through which passes a bolt 19. The bolt also passes through an eye 20 held between the jaws 18. This eye is extended into a vertically disposed eye 21 through which passes a shaft 22 carrying the yoke 23. The yoke 23 is provided with a pair of arms 24 having eyes for mounting on the shaft 22, and a second pair of arms 25 with split eyes 26 for receiving and supporting the heel clamping shaft 27.

The lower end of the shaft 22 is provided with a collar 28 which rests on top of a vertically disposed eye 29 which has a horizontally disposed eye 30 placed between the jaws 31 of the slide 17, the eye 30 and the jaws being aligned by the bolt 32.

The lower end of the shaft 22 carries a sleeve 33 from which is projected laterally a threaded shaft 34 on which is mounted an adjustable sleeve 35 carrying a jaw 36 of a link 37. This link is adjustable on the screw 38 with respect to the jaw 39 at the other end thereof. This jaw is mounted upon an adjustable sleeve 40 on the horizontally projecting screw shaft 41 carried on a collar 42 on the lower end of the shaft 27.

The sleeve 33 is provided with a jaw 43 that engages with a similar jaw 44 forming a universal joint therewith. Such jaw is mounted on the end of the shaft 45 telescopically mounted for sliding and rotary motion in a sleeve 46 which carries a jaw 47 forming a universal joint with the jaw 48 mounted on a vertical shaft 49. This shaft 49 is carried in an overhanging bracket 50 that is mounted on a dovetail member 51 that is adapted to be held in laterally adjusted position by a clamping screw 52 in the slide 53. The slide 53 is adapted to be adjusted fore and aft or to and from the operator on the slide 54 which is controlled by the set screw 55. The slide 54 is attached to the frame 1 by the bolts 54.

Beneath the bracket 50 mounted on the shaft 49 is an arm 56 carrying an adjustable sleeve 57 which is connected to the jaw 58 on the screw shaft 59 which is telescopically and adjustably mounted within the sleeve 60.

which also carries at its other end a screw shaft 61 which carries a jaw 62 at its outer end pivotally engaging at 63 with an arm 64 extending from the bottom of the heel support 65. Shafts 59 and 61 are held in their telescopic relationship within the sleeve 60 by the lock nut 66.

- The heel supporting block 65 is swivelly mounted on the upper end of the shaft 27.
- 10 It carries a heel clamping member consisting of the side plates 67 in which is pivotally mounted the heel clamping lever 68 that has the usual cam shaped forward end 69 for engaging with the upper cam-shaped surface 15 of the upper heel clamp 70. The pivotal position of the lever 68 is adjusted by the setting mechanism and adjusting screw 71. The heel blank 72 is clamped between the upper clamp 70 and the lower clamp 73.
- 20 The heel block 65 is pivotally mounted at 74 to the swivel block 75 which is mounted on the upper end of the shaft 27. The exact horizontal position or position with respect to the horizontal of the heel block 65 and the heel 25 which is clamped thereon is determined by the length of distance between the adjustable sleeve 57 and the pivotal connection 63. This adjustment is effected by the setting of the shafts 59 and 61 within the sleeve 60. This 30 effects the adjustment of the heel block to the horizontal. The bracket is swivelly mounted in the slide 51. The vertical adjustment of the heel block is accommodated by the split eyes 26 and by the adjustment of the shafts 35 37 and 38 within the sleeve 38a.

The movement of the sleeves 35 and 40 on the screw pins 34 and 41 provide for the relative distance in height and lateral position between the respective members to which they 40 are attached. It may be desirable to adjust the position of the pins 34 and 41 so that they will not lie in the same vertical plane. This adjustment between them permits of this arrangement.

45 *Method of operation.*

The knives 7 are driven rapidly by the belt 4. It is desired to move the heel blank 72 into engagement with the knives and to rotate 50 the heel blank giving the proper combined curvature characteristic of heels particularly for women's shoes.

The angularity of the heel block with respect to the knife is determined as hereinbefore explained by the distance between the sleeve 57 and the pivotal connection 63.

The heel itself has already been clamped on the heel block by the heel clamp lever 68 through the jaws 70 and 73. The tilting of 60 the heel block takes place about the pivotal point 74 on the swivel block 75. The vertical adjustment of the heel block is effected through the shaft 27 about which the heel block pivots or with which it moves.

65 If it is desired to make a lateral adjustment

of the position of the sleeve 57, that can be effected through the clamp screws 52 and 55 as hereinbefore explained. It is thus possible to modify the horizontal position or positions with respect to the horizontal of the heel block 65 and in these different positions as it moves with the shaft 27 or moves with the bracket 23 about the shaft 22.

70 It will be understood that I desire to comprehend within my invention such modifications as may be necessary to adapt it to varying conditions and uses.

75 Having thus fully described my invention, what I claim as new and desire to secure by Letters Patent, is:

80 1. In a heel turning machine, a frame, spaced cutting knives, a vertically positioned pivot shaft therebetween, a heel block supporting bracket pivoted thereon, a heel block, means to clamp a heel blank thereon, and means comprising a link to adjust the position of the heel block with respect to the horizontal.

85 2. In a heel turning machine, a frame, spaced cutting knives, a vertically positioned pivot shaft therebetween, a heel block supporting bracket pivoted thereon, a heel block, means to clamp a heel blank thereon, and means to adjust the position of the heel block with respect to the horizontal, said means comprising a link for adjusting the position 90 of the heel block with respect to the horizontal having means for being laterally positioned with respect to the frame.

95 3. In a heel turning machine, a frame, spaced cutting knives, a vertically positioned pivot shaft therebetween, a heel block supporting bracket pivoted thereon, a heel block, means to clamp a heel blank thereon, and means to adjust the position of the heel block 100 with respect to the horizontal, said means comprising a link for adjusting the position of the heel block with respect to the horizontal having means for being laterally positioned 105 with respect to the frame, and means for being positioned to and from the frame.

110 4. In a heel turning machine, a frame, cutting knives supported thereon, a heel block adapted to support a heel, means for pivotally supporting said heel adapted to bring said heel into engagement with said knives and to rotate the heel with respect to the knives, means to adjust the position of the heel block with respect to the horizontal about said pivotal means of support, means on the frame for supporting the lower end of said means for adjusting the heel block with respect to the horizontal, and means for adjustably positioning the lower end of said horizontal adjusting means laterally of said frame.

115 5. In a heel turning machine, a frame, cutting knives supported thereon, a heel block adapted to support a heel, means for pivotally supporting said heel adapted to bring said heel into engagement with said knives 120

125

130

and to rotate the heel with respect to the knives, means to adjust the position of the heel block with respect to the horizontal about said pivotal means of support, means on the 5 frame for supporting the lower end of said means for adjusting the heel block with respect to the horizontal, and means for adjustably positioning the lower end of said last named means laterally of said frame, and 10 means for connecting said lateral adjusting means and the means for adjusting the heel with respect to the pivotal supporting means for the heel block.

6. In a heel turning machine, a frame, cutting knives supported thereon, a heel block adapted to support a heel, means for pivotally supporting said heel adapted to bring said heel into engagement with said knives and to rotate the heel with respect to the 20 knives, means to adjust the position of the heel block with respect to the horizontal about said pivotal means of support, means on the frame for supporting the lower end of said means to adjust the position of the heel block 25 with respect to the horizontal, and means for adjustably positioning the lower end of said last named means laterally of said frame, and means for connecting said lateral adjusting means and the means to adjust the position 30 of the heel block with respect to the pivotal supporting means for the heel block, and means for adjusting said lateral adjusting means to and from the frame.

7. In a heel turning machine, a frame, spaced cutting knives mounted thereon, a pivot shaft mounted adjacent thereto, means for adjusting said pivot shaft with respect to said frame to and from said frame, means to swivelly mount a heel block on said shaft, a heel block having means to clamp a heel thereon, means to connect said shaft to a remotely located means for adjusting said shaft with respect to the vertical.

8. In a heel turning machine, a frame, spaced cutting knives mounted thereon, a pivot shaft mounted adjacent thereto, means for adjusting said pivot shaft with respect to said frame to and from said frame, means to swivelly mount a heel block on said shaft, a heel block having means to clamp a heel thereon, means to connect said shaft to a remotely located means for adjusting said shaft with respect to the vertical, means for adjusting the position of the heel block with respect to the horizontal.

9. In a heel turning machine, a frame, spaced cutting knives mounted thereon, a pivot shaft mounted adjacent thereto, means for adjusting said pivot shaft with respect to said frame to and from said frame, means to swivelly mount a heel block on said shaft, a heel block having means to clamp a heel thereon, means to connect said shaft to a remotely located means for adjusting the position of said shaft with respect to the ver-

tical, means for adjusting the position of the heel block with respect to the horizontal, and means for connecting said last named means to the means for adjusting the position of the pivot shaft with respect to the vertical.

10. In a heel turning machine, a frame, spaced cutting knives mounted thereon, a pivot shaft mounted adjacent thereto, means for adjusting said pivot shaft with respect to said frame to and from said frame, means to 70 swivelly mount a heel block on said shaft, a heel block having means to clamp a heel thereon, means to connect said shaft to a remotely located means for adjusting the position of said shaft with respect to the vertical, means for adjusting the position of the heel block with respect to the horizontal, and means for connecting said last named means to the means for adjusting the position of the pivot shaft with respect to the vertical, and means for adjusting laterally the position of said last mentioned means for adjusting the position of the pivot shaft with respect to the vertical.

11. In a machine, a frame, a pair of spaced 80 knife shafts vertically arranged thereon, knives thereon, a pivot shaft vertically disposed therebetween, slides in said frame for positioning said pivot shaft with respect to said frame, a swinging bracket mounted on 85 said pivot shaft, a heel clamping shaft mounted in said bracket, a heel clamping block mounted thereon, a laterally projecting screw member mounted on said heel clamping shaft, a laterally projecting screw member mounted on said pivot shaft, and means for adjustably connecting the screw members.

12. In a machine, a frame, a pair of spaced 90 knife shafts vertically arranged thereon, knives thereon, a pivot shaft vertically disposed therebetween, slides in said frame for positioning said pivot shaft with respect to said frame, a swinging bracket mounted on 95 said pivot shaft, a heel clamping shaft mounted in said bracket, a heel clamping block mounted thereon, a laterally projecting screw member mounted on said heel clamping shaft, a laterally projecting screw member mounted on said pivot shaft, and means for 100 adjustably connecting the screw members, and means for adjustably positioning the point of engagement of said connecting means with said respective screw members.

13. In a machine, a frame, a pair of spaced 110 knife shafts vertically arranged thereon, knives thereon, a pivot shaft vertically disposed therebetween, slides in said frame for positioning said pivot shaft with respect to said frame, a swinging bracket mounted on 115 said pivot shaft, a heel clamping shaft mounted in said bracket, a heel clamping block mounted thereon, a laterally projecting screw member mounted on said heel clamping shaft, a laterally projecting screw member mounted on said pivot shaft, and means for 120 125 130

adjustably connecting the screw members, and means for adjustably positioning the point of engagement of said connecting means with said respective screw members, means for adjusting the position of the pivot shaft and the heel clamping shaft.

14. In a machine, a frame, a pair of spaced knife shafts vertically arranged thereon, knives thereon, a pivot shaft vertically disposed therebetween, slides in said frame for positioning said pivot shaft with respect to said frame, a swinging bracket mounted on said pivot shaft, a heel clamping shaft mounted in said bracket, a heel clamping block mounted thereon, a laterally projecting screw member mounted on said heel clamping shaft, a laterally projecting screw member mounted on said pivot shaft, and means for adjustably connecting the screw members, and means for adjustably positioning the point of engagement of said connecting means with said respective screw members, means for adjusting the position of the pivot shaft and the heel clamping shaft, and means for laterally positioning said vertically adjustable positioning means of the pivot shaft and the heel clamping shaft.

15. In a machine, a frame, a pair of spaced knife shafts vertically arranged thereon, knives thereon, a pivot shaft vertically disposed therebetween, slides in said frame for positioning said pivot shaft with respect to said frame, a swinging bracket mounted on said pivot shaft, a heel clamping shaft mounted in said bracket, a heel clamping block mounted thereon, a laterally projecting screw member mounted on said heel clamping shaft, a laterally projecting screw member mounted on said pivot shaft, and means for adjustably connecting the set screw members, and means for adjustably positioning the point of engagement of said connecting means with said respective screw members, means for adjusting the position of the pivot shaft and the heel clamping shaft, and means for laterally positioning said vertically adjustable positioning means of the pivot shaft and the heel clamping shaft, and means for adjusting the horizontal position of the heel clamping member.

16. In a machine, a frame, a pair of spaced knife shafts vertically arranged thereon, knives thereon, a pivot shaft vertically disposed therebetween, slides in said frame for positioning said pivot shaft with respect to said frame, a swinging bracket mounted on said pivot shaft, a heel clamping shaft mounted in said bracket, a heel clamping block mounted thereon, a laterally projecting screw member mounted on said heel clamping shaft, a laterally projecting screw member mounted on said pivot shaft, and means for adjustably connecting the set screw members, and means for adjustably positioning the point of engagement of said connecting means with said

respective screw members, means for adjusting the position of the pivot shaft and the heel clamping shaft, and means for laterally positioning said vertically adjustable positioning means of the pivot shaft and the heel clamping shaft, and means for adjusting the horizontal position of the heel clamping member, said adjusting means last mentioned being connected to the means for adjusting the vertical position of the pivot shaft and the heel clamping shaft.

17. In a machine, a frame, cutting knives, a pivot shaft, vertically positioned with respect to said frame, means for adjusting the angularity of the pivot shaft with respect to the frame, a bracket carried on said pivot shaft, a heel clamping shaft carried thereby, a heel clamping block pivotally mounted thereon, and means comprising a link for adjusting the relative vertical and lateral position of said pivot shaft and heel clamping shaft.

18. In a machine, a frame, cutting knives, a pivot shaft, vertically positioned with respect to said frame, means for adjusting the angularity of the pivot shaft with respect to the frame, a bracket carried on said pivot shaft, a heel clamping shaft carried thereby, a heel clamping block pivotally mounted thereon, means for adjusting the relative vertical and lateral position of said pivot shaft and heel clamping shaft, means for adjustably positioning the elevation of the pivot shaft consisting of a sliding member adapted to be adjustably positioned to and from said frame.

19. In a machine, a frame, cutting knives, a pivot shaft, vertically positioned with respect to said frame, means for adjusting the angularity of the pivot shaft with respect to the frame, a bracket carried on said pivot shaft, a heel clamping shaft carried thereby, a heel clamping block pivotally mounted thereon, means for adjusting the relative vertical and lateral position of said pivot shaft and heel clamping shaft, means for adjustably positioning the elevation of the pivot shaft consisting of a sliding member adapted to be adjustably positioned to and from said frame, a lateral sliding member mounted on said in and out sliding member just mentioned, and a swivel bracket mounted thereon connected by a link to said pivot shaft.

20. In a machine, a frame, cutting knives, a pivot shaft, vertically positioned with respect to said frame, means for adjusting the angularity of the pivot shaft with respect to the frame, a bracket carried on said pivot shaft, a heel clamping shaft carried thereby, a heel clamping block pivotally mounted thereon, means for adjusting the relative vertical and lateral position of said pivot shaft and heel clamping shaft, means for adjustably positioning the elevation of the pivot shaft consisting of a sliding member adapted

to be adjustably positioned to and from said frame, a lateral sliding member mounted on said sliding member just mentioned, and a swivel bracket mounted thereon connected by 5 a link to said pivot shaft, an arm swivelled on said bracket, and means connected thereto for adjusting the horizontal position of said heel block.

21. In a machine for turning heels, means 10 to cut a heel, means to hold a heel to be cut, means to rotate the heel and means comprising a link to vary the angle to the horizontal of the heel during its rotation.

22. In a machine for turning heels, means 15 to cut a heel, means to hold a heel to be cut, means to rotate the heel, means comprising link structure to vary the angle to the horizontal of the heel during its rotation, and

means to vary the vertical elevation of the heel during rotation. 20

23. In a heel machine, spaced cutting means, a heel holder disposed relative thereto and pivoted therebetween symmetrically thereof, means for varying the elevating of the heel holder as it rotates about this symmetric pivot with respect to the cutting means and means for pivoting the holding means on the pivoting means for a second pivoting movement so that the distances between the pivots may be varied, and means comprising 30 link structure for varying the angularity of the heel with respect to the cutting means as the heel moves about its two centers of movement.

In testimony whereof, I affix my signature.
GEORGE CLAUSING.
